G. T. EKLUND.
SWINGING SASH CONNECTION.
APPLICATION FILED AUG. 27, 1913.

1,106,791.

Patented Aug. 11, 1914.

UNITED STATES PATENT OFFICE,

GEORG T. EKLUND, OF SAN FRANCISCO, CALIFORNIA,

SWINGING-SASH CONNECTION.

1,106,791.

Specification of Letters Patent. Patented Aug. 11, 1914.

Application filed August 27, 1913. Serial No. 763,692.

To all whom it may concern:

Be it known that I, GEORG T. EKLUND, a subject of the King of Sweden, residing at San Francisco, in the county of San Francisco and State of California, have invented new and useful Improvements in Swinging-Sash Connections, of which the following is a specification.

The present invention relates to improvements in that class of windows, which swing on a horizontal axis, for the purpose of obtaining access to both sides of the window for conveniently cleaning it.

The object of the invention is to provide means for securing the sash to the frame, such that it can be so swung on a horizontal axis without any danger of the sash dropping on account of slight imperfection of the mechanism, or of the sash being disengaged from the frame.

In the accompanying drawing, Figure 1 is a vertical section of a window frame showing in side view a sash, equipped with my invention; Fig. 2 is a section on the line 2—2 of Fig. 1; Fig. 3 is a section on the line 3—3 of Fig. 1; Fig. 4 is a section on the line 4—4 of Fig. 1 on an enlarged scale.

Referring to the drawing, 1 indicates the top, 2 the bottom and 3 a side piece of a window frame, and 4 a sash therefor. Said sash and frame are here shown as constructed of sheet metal, although it will be obvious from the following description thereof, that they can, with slight changes in the construction, be made of wood. In the inner side of said side piece 3 is formed a groove 6, which may have an angular pocket 7, known as a dust pocket, for the purpose of receiving any dust which may enter it. Secured near the top of said frame on the outer side of its face, by a pivot bolt 8, is the upper end of a hanger 9, which depends in a vertical plane at right angles to the plane of the window, and the lower portion of which is pivotally secured to the outer projecting end 10 of a bracket 11, the greater part of which is depressed and secured to the sash 4 in a groove 12 in its side. The other end of said bracket extends outwardly from said sash, and is pivotally connected, as shown at 14, to one end of a link 16, the other end of which is pivotally connected to a shoe 17, the sides of

which are, as shown at 18, bent around the edges of a vertical guide plate 19 secured by bolts 21 in the groove 6. To said link 16 is pivotally connected, at a point 22 about midway of its length, one end of an auxiliary link 23, the other end of which is pivotally connected to a shoe 24, the edges of which move in slide-ways 26 secured upon the edge of the sash, the edges of the shoe being bent up to produce a spring pressure against said slide-ways.

The top of the window sash is, at each side, slidably secured to the guide-plate 19 by a shoe 27 similar to the shoe 17. Hence if the lower portion of the sash be pressed outward, its upper portion will descend vertically, being guided by the guide-plate in the window frame.

In order to insure the sash remaining in the position to which it has been opened, I secure, by screws 29 in each edge of the sash, at the top, a guide plate 31, in the upper portion of which is a bearing 32 for a pin 33, the outer end of which is pivotally connected, as shown at 34, to the middle portion of the shoe 17, precisely similar to the shoe 17, and which has hook-shaped edges engaging the edges of the vertical guide-plate 19. Said pin is normally pressed outward by means of a bent spring 37, of which the ends are bent in the proper direction to enter a socket in the inner end of the pin, and the central portion is secured to said plate by a screw 38 and washer 39. The pressure of this spring is imparted by the pin 33 to the shoe 27 and causes said shoe to be pressed against the guide-plate 19 to exert friction thereagainst, which is sufficient to overcome the force of gravity tending to move the window sash out of the position to which it has been opened.

I claim:

In combination with a window frame, a sash, a hanger bar pivotally connected at its upper end to the window frame, and at its lower end to the side of the sash, a link one end of which is pivotally connected to a side of the sash, a shoe pivotally connected to the other end of said link and having a frictional slidable engagement with a side of the window frame, the upper portion of the sash having also a frictional slidable en-

gagement with said side of the window frame, and an auxiliary link, one end of which is pivotally connected to a mediate portion of the first-named link, and a shoe to which the other end of the last-named link is pivotally connected, said shoe having a frictional slidable engagement with said side of the sash.

In testimony whereof I have hereunto set my hand in the presence of two subscribing ¹⁰ witnesses.

GEORG T. EKLUND.
